UNITED STATES PATENT OFFICE.

JOHN C. METTLER, OF EVANSTON, ILLINOIS, ASSIGNOR TO BEARDSLEE CHANDELIER MANUFACTURING COMPANY, OF CHICAGO, ILLINOIS, A CORPORATION OF DELAWARE.

DESIGN FOR A LIGHTING FIXTURE.

Application filed October 6, 1925. Serial No. 15,037. Term of patent 7 years.

To all whom it may concern:

Be it known that I, JOHN C. METTLER, a citizen of the United States, residing at Evanston, in the county of Cook and State of Illinois, have invented a new, original, and ornamental Design for Lighting Fixtures, of which the following is a specification, reference being had to the accompanying drawing, which forms a part hereof.

My invention as illustrated relates to a suspended type of lighting fixture.

In the drawing:

Figure 1 is a perspective view of a lighting fixture showing my new design.

Figure 2 is a bottom plan view thereof.

I claim:

The ornamental design for a lighting fixture as shown.

JOHN C. METTLER.
